(57) **CLAIM**

The ornamental design for a transparent walker tray, as shown and described.

DESCRIPTION

FIG. 1 is a perspective front view of a transparent walker tray showing our new design;

FIG. 2 is a top plan view thereof;

FIG. 3 is a bottom plan view thereof;

FIG. 4 is a back elevation view thereof;

FIG. 5 is a front elevation view thereof; and,

FIG. 6 is a right side elevation view thereof, the left side being a mirror image thereof.

The broken line showing of the walker in FIG. 1 is included for the purpose of illustrating environment and forms no part of the claimed design.
